UNITED STATES PATENT OFFICE

EDWARD A. STINSON, OF WAYNE, MICHIGAN

DESIGN FOR AN AEROPLANE

Application filed March 10, 1930. Serial No. 34,808. Term of patent $3\frac{1}{2}$ years.

To all whom it may concern:

Be it known that I, EDWARD A. STINSON, a citizen of the United States, residing at Wayne, in the county of Wayne and State of Michigan, have invented a new, original, and ornamental Design for Aeroplanes, of which the following is a specification, reference being had to the accompanying drawing, forming part thereof and wherein—

Fig. 1 is a perspective view of an aeroplane showing my new design and Fig. 2 is a top plan view of the same.

I claim:

The ornamental design for an aeroplane, as shown.

EDWARD A. STINSON.
